UNITED STATES PATENT OFFICE.

ALFRED M. BIDWELL, OF JERSEY CITY, NEW JERSEY.

MATTRESS BASIN-RAIN.

1,295,844.

Specification of Letters Patent.

Patented Mar. 4, 1919.

Application filed November 23, 1916. Serial No. 132,952.

To all whom it may concern:

Be it known that I, ALFRED M. BIDWELL, a citizen of the United States, and a resident of Jersey City, county of Hudson, and State 5 of New Jersey, have invented certain new and useful Improvements in Mattress Basin-Drains, of which the following is a specification.

My invention relates to means for preventing pollution of bedding by incontinent patients, and has for its object the provision of an efficient device for this purpose, which is simple in construction and convenient in use, which is comfortable for the patient and 10 15 is readily put in place and removed, and readily cleaned and sterilized.

Another object of the invention is the provision of a mattress or mattress section so constructed as to coöperate with and permit 20 the advantageous use of my improved drain apparatus.

With the foregoing and related objects in view, my invention consists in the constructions, parts and improvements herein set 25 forth and claimed.

In the accompanying drawing I have illustrated one embodiment of my invention. In said drawing, which forms a part of this specification and wherein the same reference 30 numerals designate the same parts throughout, Figure 1 is a top plan view showing a bed mattress in three parts with the center part constructed to receive and equipped with my improved basin drain. Fig. 2 is 35 a transverse cross-sectional view on line 2—2, Fig. 1.

While basin drains in accordance with my invention may be made use of with any mattress, I prefer to make use therewith of 40 a three section mattress such as is ordinarily provided in modern hospitals, the mattress consisting of three separate sections with the divisions therebetween running cross-wise of the bed, as shown in Fig. 1. As certain structural features of the mattress are 45 important, the section containing the basin drain being specially constructed to receive the same, the use of a three part mattress is preferable, since, in order to utilize my invention, it is only necessary to remove the center section and to substitute one of my specially constructed center sections and to provide the accompanying basin and drain.

10 designates the mattress made up of like 55 sections 11 and 12. Ordinarily a third like intermediate section completes the mat-

tress, but when my invention is to be utilized a specially constructed mattress section, preferably of the same size as sections 11 and 12, is provided. This mattress drain section 13 is in two parts, a principal part 14 having a preferably circularly ended slot or recess 15 therein and extending to the side 16 of the bed, and a smaller mattress part 17 fitting in the slot or recess 15 so as to leave the preferably circular opening 18 substantially in the center of the bed and said part 17 extending to the open end of the slot or recess 15 so as to fill out the mattress section 13 flush with the side of the bed. 60 65 70

This central opening 18 is left to accommodate the device 19, which I shall refer to as a "basin". It is preferably circular in form and has a preferably flat bottom 20, and on its upper portion 21 comprises a central drain pan 22 and an annular seat 23 for receiving a preferably pneumatic annular pad or ring 24 encircling the pan 22, affording an easy and comfortable support for the patient. The side walls 25 of the 80 basin, with the bottom 20 and top portion 21, preferably form a permanently closed hollow structure which is light and sanitary, as no polluting fluids come into contact with its interior space 26. The bottom 20 of the 85 basin 19 preferably rests on the mattress support, as the bed springs, and a drain pipe 27 communicates with the drain pan 22, preferably at the central and lower part thereof, as at 28. This drain pipe at its 90 inner end is received within the hollow interior 26 of the basin and extends laterally, projecting from the side wall 25, beneath the mattress section 17, resting on the springs or other mattress support and is directed 95 downwardly at its outer end as by being provided with an elbow 29 preferably having a bore flush with the bore of the pipe 27, the said elbow being preferably screwed on by hand and not screwed up fixedly, so that it 100 may readily be removed so as to facilitate the cleaning of the device.

As all the parts of the basin and drain are of metal, they may be readily cleaned and sterilized, and when the basin is to be 105 removed it can be drawn out on the side of the bed by first removing the removable mattress section, or the mattress section 17 and basin may be removed together.

The operation and utility of the invention will be apparent from the foregoing. While I have described the preferable em-

bodiment, it will be apparent that changes therein and modifications therefrom may be resorted to within the scope of my claims and without sacrificing the advantages of 5 my invention.

Having thus described my invention, I claim:

1. A mattress provided with a recess extending to the side thereof, a basin in said 10 recess and adapted to be supported above the bed spring or other mattress support, a removable mattress section in said recess and extending to the side of the mattress, and a drain also adapted to be supported above the 15 bed spring or other mattress support and extending from said basin beneath the removable mattress section.

2. A mattress basin drain comprising a central mattress section for a multiple section mattress, said section having a slot 20 therein extending to the side thereof and a removable mattress part in said slot, a basin in said recess and adapted to be supported above the bed spring or other mattress support, and a drain pipe for said basin also 25 adapted to be supported above the bed spring or other mattress support and extending out beneath the removable mattress piece.

In testimony that I claim the foregoing, I 30 hereto set my hand, this 21st day of November, 1916.

ALFRED M. BIDWELL.
